UNITED STATES PATENT OFFICE.

JAMES R. HAZELEY, OF PHILADELPHIA, PENNSYLVANIA.

TIME-LOCK.

SPECIFICATION forming part of Letters Patent No. 601,341, dated March 29, 1898.

Application filed May 12, 1897. Serial No. 636,174. (No model.)

To all whom it may concern:

Be it known that I, JAMES R. HAZELEY, a citizen of the United States, residing in the city of Philadelphia, county of Philadelphia, 5 State of Pennsylvania, have invented certain new and useful Improvements in Time-Locks, of which the following is a specification.

My invention is more particularly a time-lock for toy savings-banks; and its objects are, 10 first, to provide a simple and efficient lock which may be set to run for any desired period of time within a certain limit; second, to provide simple and efficient means for increasing the time for which the lock has been 15 set after the bank has been closed and the time limited has begun to run, and, third, to provide simple and efficient means for preventing a decrease of the time limited after 20 the bank has been closed or to prevent tampering with the mechanism and opening the bank within the period for which the lock has been set. These ends are attained by the mechanism illustrated in the accompanying drawings, of which—

25 Figure 1 is a front elevation of a time savings-bank embodying the invention. Fig. 2 is an interior view, in end elevation, illustrating the arrangement of the money-drawer and safe. Fig. 3 is a front elevation of the 30 interior mechanism, the casing being broken away for the purpose of illustration. Fig. 4 is a plan view, partially in section, the clock and a section of the casing being broken away for the purpose of illustration. Fig. 5 is an 35 end elevation of the interior mechanism illustrated in front elevation in Fig. 3. Fig. 6 is a plan view of the mechanism for actuating the locking-bolts. Fig. 7 is a longitudinal sectional view of the mechanism for increasing 40 the time limit and for preventing the decrease thereof. Fig. 7^a is a view on the line *a a* of Fig. 7, and Fig. 8 is a side view of the latch-bolt shown in operative position in Figs. 4 and 7.

45 Referring to the drawings, a clock of ordinary construction is supported by a frame 1, which is secured to the casing-frame 2 by means of blank-headed bolts 3, passed through the lugs 4 of the casing-frame and held in 50 place by nuts 5, which are covered by the clock-face 6. The use of the blank-headed bolts having their nuts covered by the clock-

face, which is clamped in place by the casing 6', prevents the detachment of the clock from the locking mechanism, which would otherwise be readily accomplished and the movement thus tampered with.

55 The usual spring 7 and pinion 8 drive the lock-train, the pinion 8 gearing with a small pinion 9, which is fixed on an arbor 10, journaled in a bearing 11 of the casing-frame. The revolving arbor 10 has a small pinion 12 fixed thereon, which gears with a large pinion 13, revolving it and the small pinion 14, fixed thereto, on an arbor 15, supported by the casing-frame. The pinion 14 gears with a large pinion 16, revolving it and a small pinion 17, fixed thereto, on an arbor 18, supported by the casing-frame. The pinion 17 gears with 60 and revolves the large pinion 19, having the 65 hub 20, which rotates upon an arbor 21, fixed in the hub 22 of the casing-frame, the mechanism described being supported on the safe-lid 23. The end of the hub 20 is provided with four holes 24, which are placed about 70 the axis of the hub equidistant therefrom and from each other.

75 A barrel 25, having a worm or screw-threaded section 26, is journaled in a casing or cover 27, having bearings 28 therefor. A shaft 29, 80 having a screw-threaded end 30, extends through the barrel 25 and into the hub 20, the shaft being permitted longitudinal movement within the hub and being prevented from revolving independently thereof by means of a 85 pin 31, fixed in said shaft, which moves longitudinally in a channel 32, formed in the barrel, said pin and channel limiting the backward movement of said shaft. The pin 31 projects through the shaft and plays in a 90 recess 35, formed in a bolt 33, which is adapted to reciprocate in a channel 32', formed in the barrel, the pin being designed to draw the bolt back a limited distance, while the recess permits the bolt further backward movement after the pin has reached its limit or the 95 end of the channel 32. A coiled spring 36 lies in the bottom of the channel 32' and behind the bolt 33, which it tends to thrust forward into one of the holes 24 when presented, while the beveled face 34 on the outer end of the bolt provides means for forcing the bolt out of the hole 24 which it may occupy, permitting the barrel 25 to be turned to the right 100

independently of the hub 20 and preventing it from being turned to the left, the pin 31 being designed to draw the bolt back to the inner limit only of the beveled face 34 and 5 its total withdrawal being effected by screwing the key 37 on the end of the shaft 29, which when turned to the right rotates the shaft, but when turned to the left merely detaches itself. Provision is thus made for retarding the release of the lock.

The worm 26 engages the teeth of a gear-wheel 39, which is fixed on an arbor 40, journaled in the safe-lid 23. Beneath the lid and fixed on the arbor 40 by means of a set-screw 15 40' is a wheel 41, provided with a dial 41', preferably placed on the periphery of the wheel. A notch 42 is formed in the periphery of said wheel, and a pawl or spring-arm 43 is secured to the face thereof at a fixed distance 20 from said notch. The pawl has its free end extending backward from said notch and elevated above the lower end of a pin 44, fixed in the lid, the pawl permitting the notched wheel to revolve continuously forward, for it will slip past the pin, but preventing its rotation backward beyond a limited 25 arc by engaging with the pin.

A shaft 45 is pivoted within the safe at 46 and has arms 48 and 49 fixed thereon. Each 30 arm 48 is provided with a bolt 50, which lies in a channel 51, formed in the upper end of the arm, the bolt having a slot 52, through which and the arm a pin 53 passes, securing the bolt in position, but permitting it limited 35 backward movement against the action of a spring 54, secured to the arm. A nose 55 on the bolt is adapted to engage a catch 56 on the lid to lock the safe, as illustrated in Fig. 5. Both the nose and the catch have their 40 outer faces beveled, so that the latter descending and striking the former may thrust it back against the action of the spring, which restores the bolt to its normal position and locks the lid when the catch has passed the 45 nose.

The arm 49 has its top 49' beveled to conform to the notch 42, into which it is forced by a spring 47, secured to the arm and bearing against the front wall of the safe, when 50 the notch in its revolution is brought into registration with the arm. During the revolution of the wheel 41 through its entire arc its periphery holds the arm 49 back, and thus, rocking the shaft 45 and the arms 48, locks 55 the lid, as illustrated in Figs. 5 and 6; but when the notch at the end of a complete revolution of the wheel registers with the arm 49 the latter is thrown forward by its spring, thus rocking the shaft 45 and the arms 48, 60 whereby the lid is released.

The position of the notch 42 with reference to the arm 49, and consequently the time of the release of the lock, is marked by a hand 57, which is fixed on the arbor 40 and travels 65 over a dial 58, formed on the casing 27.

The deposit is made by drawing out either

of the drawers 59, which may be provided with bottoms 60, pivoted at 61, so that when the drawer occupies the closed position the bottom drops down, as illustrated in Figs. 2 70 and 3, permitting the coin or other deposit to fall into the safe, and when the drawer is drawn out the bottom is thereby elevated and the passage to the safe closed.

In operation the lock-train may be constructed to effect a complete revolution of the notched wheel 41 and the consequent release of the lock at the expiration of any desired period of time, which for the purpose of illustration may be fixed at three hundred 80 and sixty days. The lock-train is consequently so designed that the forty-eight-toothed pinion 8 operates a train consisting of a sixteen-toothed pinion 9, a twenty-toothed pinion 12, a sixty-toothed pinion 13, a twenty-toothed pinion 14, an eighty-toothed pinion 16, a twenty-toothed pinion 17, and an eighty-toothed pinion 19, which effects one revolution of the hub 20 and the barrel 25 in four days. The worm 26 on the barrel drives a ninety-toothed wheel 39, which revolves the notched wheel 41 through its entire arc in three hundred and sixty days, upon the expiration of which the lock releases through the operation of the arm 49 in dropping into 95 the notch and thereby withdrawing the bolts 50. If at any time during the period for which the lock has been set to run it is desired to increase this time, this may be accomplished by screwing the key 37 on the shaft 29, drawing the shaft back to its limit, and then turning it to the right, thereby withdrawing the bolt 33 from the hole 24 with which it has engaged, and increasing the time by as many days as the bolt is turned through 100 quadrants marked by the holes 24. If it is desired to have the lock release at the expiration of a month or other short period of time, the mechanism may be set to this time before the bank is closed by releasing the set-screw 40' and turning the wheel 41 until its 105 notch 42 occupies the desired position relative to the arm 49, which position may readily be found by means of the dial 41'.

Having described my invention, I claim— 115

1. The combination of a clock with a safe, a bolt which normally locks said safe, mechanism operated by said clock which actuates said bolt to lock said safe for a definite period of time and to release at the expiration thereof, and mechanism for increasing said definite period of time at any instant during said period, as shown and described.

2. The combination of a clock with a safe, a bolt which normally locks said safe, and a locking-train operated by said clock which actuates said bolt to lock said safe for a definite period of time and to release at the expiration thereof, said locking-train comprising a pinion, a barrel normally connected 120 with and revolved by said pinion, and means for revolving said barrel independently of 125

said pinion for increasing said definite period of time at any instant during said period, substantially as specified.

3. The combination of a clock with a safe, 5 a bolt which normally locks said safe, and a locking-train operated by said clock which actuates said bolt to lock said safe for a definite period of time and to release at the expiration thereof, said locking-train comprising a pinion, a barrel normally connected with and revolved by said pinion, and a spring-actuated latch-bolt which permits the retardation of said barrel and prevents the acceleration thereof relative to the revolution 15 of said pinion, thereby increasing said definite period of time and preventing the decrease thereof, substantially as specified.

4. The combination of a pinion and a hub thereon, with a barrel and a latch-bolt therein 20 which normally engages said hub and rotates said barrel therewith, an axial shaft adapted to move longitudinally in said barrel and extending therethrough into said hub, and means on said shaft for partially withdrawing 25 said latch-bolt from said hub and turning said barrel whereby said latch-bolt is wholly withdrawn from said hub and said barrel turned back relative thereto, substantially as specified.

30 5. The combination of a pinion with a barrel which is normally revolved thereby, means connecting said pinion and barrel permitting the retardation of said barrel and preventing the acceleration thereof relative to the revolutions of said pinion, a worm formed on said barrel, and a gear-wheel operated by said worm, as specified.

6. The combination of a pinion with a barrel which is normally revolved thereby, means 40 connecting said pinion and barrel permitting the retardation of said barrel and preventing the acceleration thereof relative to the revolutions of said pinion, a worm formed on said barrel, a revoluble shaft and a gear-wheel 45 thereon operated by said worm, and a notched wheel fixed on said shaft, substantially as specified.

7. The combination of a pinion with a barrel which is normally revolved thereby, means 50 connecting said pinion and barrel permitting the retardation of said barrel and preventing the acceleration thereof relative to the revolutions of said pinion, a worm formed on said barrel, a revoluble shaft and a gear-wheel 55 fixed thereon operated by said worm, a notched wheel fixed on said shaft, a pawl on said notched wheel, and a fixed pin which engages said pawl and prevents a complete backward revolution of said notched wheel, as 60 specified.

8. The combination of a revoluble notched wheel, with means for rotating said wheel, a rock-shaft, an arm fixed on said shaft and oscillated thereby, a spring-controlled bolt 65 fixed to said arm and movable relatively thereto, a lid and a catch thereon adapted to be engaged by said bolt, and a spring-actuated arm

which normally bears against the periphery of said wheel by which said bolt is held in engagement with said catch, said spring-actuated arm dropping into the notch of said wheel to withdraw said bolt from engagement with said catch, substantially as specified. 70

9. The combination of a clock with a safe, 75 a rock-shaft pivoted in said safe, an arm fixed on said shaft and oscillated thereby, a bolt fixed to said arm and operated thereby, a lid and a catch thereon adapted to be engaged by said bolt, a second arm fixed on said shaft and oscillated thereby, and a locking-train 80 comprising a barrel driven by said clock and a worm thereon, a revoluble shaft and a gear-wheel fixed thereon operated by said worm, a notched wheel fixed on said revoluble shaft, and means for holding said second arm in 85 contact with the periphery of said notched wheel, for the purpose set forth.

10. The combination of a pinion and a hub thereon having holes in its end, with a barrel and a latch-bolt therein having a beveled end 90 which engages with said holes, an axial shaft adapted to move longitudinally in said barrel and extending therethrough into said hub, a pin fixed in said shaft which permits limited longitudinal movement thereof relative 95 to said barrel and hub and prevents rotary movement thereof relative to said barrel, said pin having a loose connection with said bolt whereby the latter may be partially withdrawn from said holes, and a spring which 100 tends to thrust said bolt forward into said holes, as specified.

11. The combination of a clock with a safe, a bolt actuated by said clock which normally locks said safe for a definite period of time, 105 mechanism by which said definite period may be decreased at will previous to the locking of said safe so that said bolt will release at the expiration of any previously-selected period, and mechanism for increasing said selected 110 period of time at will after the locking of said safe, as specified.

12. The combination of a clock with a safe, a bolt which normally locks said safe, and a locking-train which is operated by said clock 115 and actuates said bolt to lock said safe for any desired period of time within a definite limit and to release at the expiration of said desired period, said locking-train comprising a worm, a gear-wheel actuated by said worm, 120 an arbor upon which said gear-wheel is fixed, a notched wheel fixed on said arbor, means for varying the relative position of said notched wheel with reference to said gear-wheel, and mechanism connecting said lock-bolt with 125 said notched wheel by which said notched wheel both locks and releases said safe, as specified.

In testimony whereof I have hereunto set my hand this 11th day of May, A. D. 1897.

JAMES R. HAZELEY.

In presence of—

THOMAS S. GATES,
WILLIAM J. FISHER.
